SPACE HEATER CONSTRUCTION

Albert H. Crone, Rockford, Ill., assignor to Geo. D. Roper Corporation, Rockford, Ill., a corporation of Illinois

Application May 13, 1953, Serial No. 354,793

2 Claims. (Cl. 257—151)

This invention relates to a space heater construction, and has particular reference to a space heater of the type employing a gas burner and intended for assembly on a gas stove for heating the kitchen where the stove is situated.

It is an object of this invention to provide a novel and improved space heater construction adapting the heater for high efficiency operation.

Heretofore, in heaters of this general type the general practice has been to attempt to store the greatest amount of heat possible within a radiator and to rely on this to heat the air outside the radiator sufficiently for the heater to be effective for its intended purpose. However, no particular consideration was given to the paths followed within the radiator by the hot products of combustion from the gas burner, so as to render these products of combustion most effective to heat the wall areas of the radiator exposed to the outside air to be heated.

In the present invention, the hot products of combustion from the gas burner are directed within the radiator to sweep along a greater area of the outer side walls of the radiator, with part of the products of combustion sweeping over substantially all of the radiator wall areas exposed at their outer faces to the air to be heated. With this arrangement, the air passing along the outer side wall surfaces of the radiator is heated quickly and efficiently and the overall heat transfer characteristics of the heater are greatly improved.

It is, therefore, another object of the present invention to provide a novel heater construction in which hot products of combustion are directed within the radiator across a maximum of the radiator wall area which is exposed at its outer surface to the air to be heated.

Also, it is an object of this invention to provide a novel heater construction in which part of the products of combustion from a gas heater which flow up one side of the radiator are directed to then pass up the other side of the radiator before being discharged from the radiator, thus extracting an increased amount of heat from these products of combustion before they are discharged.

Other and further objects of the present invention will be apparent from the following description of a preferred embodiment thereof, illustrated in the accompanying drawing.

In the drawing:

Figure 1 is a fragmentary perspective view of a stove which incorporates the space heater of the present invention;

Figure 2 is a top plan view, partly broken away, showing the radiator construction in the present heater;

Figure 3 is a longitudinal elevational view of the present heater, partly broken away to better illustrate details of its construction; and

Figure 4 is an end view, partly broken away, of the heater.

Referring to the drawings, in the present heater assembly there is provided a conventional elongated gas burner 10 having a series of upwardly directed flame ports 11,

2

12 on either side along its length. The burner is located at the lower end of a radiator having a bottom opening 13 along its length for admitting air to flow up past the burner.

5 The radiator body is in the form of two cast sections 14 and 15, of cast iron or cast aluminum, which are bolted together at their interface 16, which extends lengthwise from one end of the radiator to the other substantially along the centerline thereof.

10 The casting 15 of the radiator body has an upwardly extending side wall 17 which is flat at its inner face throughout substantially its entire extent, including a lower portion 18 which inclines outward and upward at a slight angle and a vertical portion 19 extending upward therefrom. At its upper end the side wall 17 merges smoothly with the curved top wall 20 of this casting of the radiator body, this top wall being generally sinuous longitudinally of the radiator and providing a plurality of channels 21. A plurality of outwardly projecting heat-radiating fins 22 are provided which extend continuously across the top wall and down along the side wall of the radiator body casting 15, terminating somewhat above the bottom of the radiator body. At one end the casting 15 of the radiator body is formed with an integral discharge mouth 24 positioned just higher than the juncture between the inclined and vertical surfaces 18 and 19 of the side wall 17 and located about one-third of the way down from the top of the radiator body.

15 The other casting 14 of the radiator body has an outer side wall formed by a plurality of substantially flat segments 25 which are interconnected by outwardly protruding channel-shaped segments 26 which provide a plurality of channels 27. The flat wall segments 25 incline inwardly in a direction upward along the radiator body, while the channel-shaped segments 26 incline outwardly in an upward direction, so that the channels 27 increase in depth upward along the radiator body. Both the flat and channel-shaped portions of the side wall merge smoothly with respective portions of the curved top wall. This top wall has a sinuous shape longitudinally of the radiator body, substantially identical to the shape of the top wall 20 of the other body casting 15 of the radiator and provides a plurality of spaced, inwardly disposed segments 28, forming continuations of the flat side wall segments 25, and spaced channel-shaped segments, which form continuations of the side wall channel-shaped segments 26 and which define channels 29 receiving the products of combustion rising up the passages 27. These top channels 29 in the radiator body casting 14 communicate with respective ones of the channels 21 in the top wall 20 of the other radiator body casting 15. A plurality of outwardly protruding, heat radiating fins 30 extend down along the top and side walls of casting 14 of the radiator body.

20 55 For directing certain of the flows of the hot products of combustion in the radiator body there is provided a sheet metal baffle (Fig. 4) of irregular configuration including a flat, upwardly extending portion 31 directly underlying the upper portions of the flat, inwardly disposed, side wall segments 25 of the radiator body casting 14, a curved top portion 32 directly underlying the inwardly disposed segments of the curved top wall 28 of radiator body casting 14 which separate the channels 29 therein, the flat, substantially horizontal portion 33 which directly underlies the inwardly disposed segments of the top wall 20 of radiator body casting 15 which separate the channels 21, a vertical section 34 extending in spaced parallel relation to the vertical section 19 of the side wall 17 of radiator body casting 14 and a horizontal portion 35 extending across for attachment at its upstanding flange 36 to the vertical section 19 of the side wall 17. From the drawings, it will be apparent that

the baffle 31-36 extends across the top of communicating internal chambers 14a and 15a in the respective radiator body castings 14 and 15. The portions 31 and 32 of the baffle, which underlie the innermost wall segments of the side and top walls of the radiator body casting 14, separate the respective side channels 27 from one another and separate the respective communicating top channels 29 from one another, and require the heated products of combustion to pass in separate flows through these channels, as best seen in Figs. 2 and 3. Likewise, the flat horizontal upper portion 33 of the baffle, which underlies the lowermost segments of the sinuous top wall 20 of the radiator body casting 15, separates the respective top channels 21 therein and requires the heated products of combustion to flow in separate streams therethrough from the separate top channels 29 in the other radiator body casting 14. Since the discharge outlet 24 communicates with the space between the sinuous top wall 20 and the vertical portion 19 of the side wall of the radiator body casting 15, on one hand, and the baffle wall portions 34-36, on the other hand, all of the top channels 21 in the radiator body casting 15 communicate with the discharge outlet to pass the heated products of combustion thereto. The baffle is suitably secured to the respective body sections of the radiator, as by screws 37. Since the baffle extends the entire length of the radiator body, it limits the upward flow of the heated products of combustion within the chamber 15a and along the side wall 17 and directs these products of combustion over to the channels 27 at the other side of the radiator body.

In the use of this heater, the radiator is mounted within a compartment at one end of the stove 40, which has an outlet 41 for heated air in its end wall 42. The radiator has its side wall 17 closest to the end wall 42 of the stove. Gas is supplied to the burner 10 from a conduit 43. The bottom of the radiator is located several inches off the floor. A discharge stack 44 is connected to the outlet 24 for passing the products of combustion out of the kitchen.

In operation, with the gas burner 10 lighted, air flows up past the burner on opposite sides thereof to provide secondary air supporting combustion at the burner. The heated products of combustion from the burner then pass up into the radiator body. A portion of these hot products of combustion sweep across the outer side wall of the radiator body casting 14, passing up through the separate channels 27 and thence through the communicating channels 29 and 21, and down along the vertical portion 19 of the side wall 17 of the other radiator body casting 15, to the discharge outlet 24, where they are exhausted through the stack 44. The remainder of the heated products of combustion from the burner, which initially pass up into the other radiator body casting 15, are deflected by the baffle plate 31-36 after sweeping across the inclined lower portion 18 of the side wall 17, and are directed to the channels 27 at the opposite outer side wall of the radiator body, from which they follow the above-described path to the stack 44. The air outside the radiator body sweeps up along the outside of the radiator body upward along both sides thereof and across the top to the heated air discharge openings 41 in the stove end wall 42. Normally, sufficient air flow occurs in this manner due to the inherent stack action of the heater, with the air rising along the outside of the heater and passing out the openings 41, without the necessity of providing a blower to force air past the radiator body.

From the foregoing it will be seen that with the disclosed construction of the present invention, the heated products of combustion are directed in a positive manner to sweep across the inside of substantially all of the exposed outer wall area of the radiator body, so as to heat these radiator walls rapidly and effectively. In addition a portion of the heated products of combustion are directed to sweep across both sides and the top of the

radiator body before being discharged therefrom, so that an increased amount of heat is extracted from these products of combustion for heating the wall area of the radiator body exposed to the outside air to be heated.

While in the foregoing description and in the accompanying drawing there is disclosed a particular preferred embodiment of the present invention, it is to be understood that various modifications, omissions and refinements which depart from the disclosed embodiment of the invention may be adopted without departing from the spirit and scope of the present invention.

I claim:

1. A heat radiator comprising a pair of castings secured together at abutting interfaces and formed with internal chambers which communicate with one another at the abutting interfaces of the castings, one of said castings having an upwardly extending outer side wall providing a plurality of upwardly extending channels communicating with the chamber in said casting, said one casting having a top wall of sinuous configuration defining a plurality of top channels communicating respectively with said upwardly extending channels and forming continuations of said upwardly extending channels and extending across the top of said internal chamber in said casting, the other of said castings having a substantially flat upwardly extending side wall at said chamber therein, a heated products inlet communicating with said chambers adjacent the bottom thereof, said other casting having a top wall of sinuous configuration extending across the top of the chamber in said other casting and defining a plurality of top channels communicating respectively with said top channels in said one casting and forming continuations thereof, a baffle overlying the upper end of the chamber in said one casting and underlying the inner face of the innermost segments of said upwardly extending side wall thereof and directly underlying the inner face of the lowermost segments of said top wall of said one casting to separate the upwardly extending channels from one another and to separate the top channels in said one casting from one another to require heated products to pass in separate flows up through said upwardly extending channels and through said top channels in said one casting, said baffle terminating above the lower end of the side wall of said one casting whereby the heated products may pass from said chambers into the upwardly extending channels in said one casting adjacent the lower ends thereof, said baffle overlying the top of the chamber in said other casting and directly underlying the inner face of the lowermost segments of said top wall of said other casting to separate the top channels in said other casting, said baffle extending downwardly from said top wall of said other casting and across said chamber in said other casting in spaced relation to the top wall thereof into engagement with said side wall of the other casting to form a heated products outlet passage therewith and to limit the flow of heated products upward along said side wall of the other casting and to direct said heated products across to the chamber in said one casting to pass into said separate upwardly extending channels in said one casting for separate flows therethrough and through said top channels in both castings, and a discharge opening for heated products at said other casting in communication with said heated products outlet passage.
2. A heat radiator comprising a pair of castings formed with mating flanges along the top and ends thereof, fasteners securing said sections together with the flanges thereon in abutting relation to define an internal chamber having an open bottom forming a heated products inlet, one of said castings having a side wall extending upwardly and inwardly, said side wall having a plurality of upwardly extending channels formed therein of progressively increasing depth from the bottom to the top thereof with the apexes of the channels defining a plane which diverges outwardly from said side wall, said channels being

spaced apart lengthwise of said one casting and communicating with said chamber, said one casting having a top wall of sinuous configuration defining a plurality of horizontally extending channels forming continuations of said upwardly extending channels, the other casting having a substantially flat side wall extending upwardly and outwardly and a top wall of sinuous configuration extending across the top of said chamber and defining a plurality of channels communicating with the channels in the top wall of said one casting and forming continuations thereof, said other casting having a heated products outlet opening in the end thereof below the channels in the top wall, a baffle formed of a single piece and secured to said side wall in said one casting intermediate the upper and lower ends thereof and extending upwardly along said side wall to separate the channels therein from one another and cause the heated products in the chamber to pass in separate flows through said upwardly extending channels, said baffle extending along the top walls in said castings to a point spaced from the side wall in said other casting 20 to separate the channels in said top walls from each other,

said baffle extending downwardly from the top wall in spaced relation to the side wall in the other casting and horizontally across the chamber into engagement with the side wall in said other casting to define a heated products passage therewith and to limit the flow of heated products upward along said side wall in the other casting and to direct the heated products flowing along the side wall in said other casting across the chamber into the upwardly extending channels in said one casting, and means for securing said baffle to the side walls of each of said castings.
